DESIGN FOR A THERMOSTAT CASING OR SIMILAR ARTICLE

Clarence Karstadt, Glen Ellyn, Ill., assignor to
Sears, Roebuck and Co., Chicago, Ill., a cor-
poration of New York

Application August 25, 1939, Serial No. 86,890

Term of patent 7 years

To all whom it may concern:

Be it known that I, Clarence Karstadt, a citizen of the United States, residing at Glen Ellyn, in the county of Du Page and State of Illinois, have invented a new, original, and ornamental Design for a Thermostat Casing or Similar Article, of which the following is a specification, reference being had to the accompanying drawing, forming a part thereof.

Fig. 1 of the drawing is a perspective view of a thermostat casing or similar article embodying my new design.

Fig. 2 is a top plan view of the same.

Fig. 3 is a bottom plan view of the same.

I claim:

The ornamental design for a thermostat casing or similar article, substantially as shown.

CLARENCE KARSTADT.
